(57) **CLAIM**

The ornamental design for a tool box handle, as shown and described.

DESCRIPTION

FIG. 1 is a left rear perspective view of my new design.

FIG. 2 is a top view thereof.

FIG. 3 is a bottom view thereof.

FIG. 4 is a left side view thereof.

FIG. 5 is a right side view thereof.

FIG. 6 is a front view thereof; and,

FIG. 7 is a rear view thereof.

The broken lines in the drawings illustrate portions of the tool box handle and form no part of the claimed design.
